Primary Examiner — Selina Sikder(74) *Attorney, Agent, or Firm* — Tyler J. Sisk; Casimir Jones, S.C.(57) **CLAIM**

The ornamental design for a switch, as shown and described.

DESCRIPTION

FIG. 1 is a three-quarter perspective view showing our new design of a switch;

FIG. 2 is a front elevational view thereof, the rear elevational view being identical;

FIG. 3 is a left side elevational view thereof,

FIG. 4 is a right side elevational view thereof,

FIG. 5 is a top plan view thereof; and,

FIG. 6 is a bottom plan view thereof.

The broken lines shown in FIGS. 1 through 6 are for the purpose of illustrating environment, and form no part of the claimed design.

1 Claim, 1 Drawing Sheet(56)
